UNITED STATES PATENT OFFICE.

THOMAS H. SAUNDERS, OF BOSTON, MASSACHUSETTS.

SCRUBBING-BRUSH.

SPECIFICATION forming part of Letters Patent No. 393,522, dated November 27, 1888.

Application filed October 27, 1887. Serial No. 253,539. (No model.)

To all whom it may concern:

Be it known that I, THOMAS H. SAUNDERS, a citizen of the United States, residing at Boston, in the county of Suffolk and State of Massachusetts, have invented certain new and useful Improvements in Scrubbing-Brushes; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

Figure 1 is a top view, Fig. 2 a side elevation, Fig. 3 a longitudinal section, and Fig. 4 a transverse section, of a scrubbing-brush provided with my invention.

The nature of my invention is set forth in the claims hereinafter presented.

In the drawings, A denotes a scrubbing-brush, to the top of which is secured a bellows, B. In the top of said bellows is an opening, a, in which is inserted a stopper, b. Said stopper is provided with a vertical passage, c, which opens into conduits d d. This bellows is to be supplied with a finely-powdered scouring material or a saponaceous powder, as may be desired, access being had to the interior of the bellows to enable it to be charged with the above-mentioned material by removing the stopper b from the opening a.

Secured to the top of the brush is a bracket, e, provided with two ears, to which is pivoted a cammed lever, f. There is arranged under said cammed lever and between the ears of the bracket a flexible hose or tube, g, which passes down through a hole, h, in the top of the brush and terminates among the bristles of the brush, as shown in Fig. 3. At its outer end it is provided with a nozzle, i, as shown in Fig. 1.

In using the above-described brush on a floor the nozzle i is to be inserted in an opening in the lower portion of a water-bucket, the cammed lever being turned so as to close the hose g, and said hose is to be of sufficient length

to allow of the proper or necessary movement of the brush over and upon the surface of the floor by the hand of an attendant as an ordinary scrubbing-brush would be used. On raising or allowing the end of the cammed lever to rise into the position shown in Fig. 3 water will flow through the hose to the bristles of the brush as may be required, and by raising and forcing down the top of the bellows the contents thereof will be forced out through the conduits d onto the floor, as circumstances may require. Thus it will be seen that my scrubbing-brush can be readily supplied with water and the floor with a scouring or cleansing material while the brush is being moved about upon the surface thereof, and the flow of water to the brush can be regulated by varying the pressure of the palm of the hand on the end of the cammed lever while grasping the brush.

Having described my invention, what I claim is—

1. The scrubbing-brush having a bellows, B, with the plug b, having a passage, c, leading into the bellows and connected with the orifice of the double-branched pipe d d, constructed, as described, to discharge the contents of the bellows upon the surface to be cleansed.

2. The combination of the scrubbing-brush A, provided with a hose for supplying it with water, and a cam-lever, f, for checking or regulating the flow of the water from a reservoir or bucket, with the bellows B, to contain a powdered scouring or cleansing material, said bellows having passages and tube d on each side thereof, through which said scouring or cleansing material can be ejected therefrom onto the surface to be scoured or cleansed, all as shown, and substantially as set forth.

In testimony whereof I affix my signature in presence of two witnesses.

THOMAS H. SAUNDERS.
